UNITED STATES PATENT OFFICE.

ALICE MIRIAM WOOD, OF MUSKEGON, MICHIGAN.

TOY TOBOGGAN.

SPECIFICATION forming part of Letters Patent No. 429,492, dated June 3, 1890.

Application filed September 6, 1889. Serial No. 323,189. (No model.)

To all whom it may concern:

Be it known that I, ALICE MIRIAM WOOD, a citizen of the United States, residing at Muskegon, in the county of Muskegon and State 5 of Michigan, have invented certain new and useful Improvements in Toy Toboggan-Slides; and I do hereby declare the following to be a full, clear, and exact description of the invention, such as will enable others skilled in 10 the art to which it appertains to make and use the same.

This invention has reference to a toy toboggan-slide, the object thereof being to construct 15 a toboggan-slide in the form of a cheap, simple, and useful toy; and the invention consists in the construction, arrangement, and combination of parts, substantially as will be hereinafter described and claimed.

In the accompany drawings, illustrating my 20 invention, Figure 1 is a vertical section in partial elevation of my improved toy toboggan-slide, showing the several parts arranged in normal position with the toy ready for use. Fig. 2 is a top plan view of the same. Fig. 3 25 is a bottom plan view showing the legs or supports and also the steps folded up.

Similar letters of reference designate corresponding parts throughout the different figures of the drawings.

30 A denotes the incline. This incline is a board or flat surface of greater or less length and of suitable width. Its upper face near the longitudinal edges is provided with flanges or narrow strips *a a*, secured thereto so as to prevent 35 the edges of the inclined surface from splitting, checking, or roughening, and at the same time to furnish a suitable finish for said inclined surface A is supported in its inclined position by means 40 of suitable adjustable folding legs. One end of the incline is designed to rest upon the ground or floor or other supporting object. At the other or highest end of the incline it is supported by means of a pair of legs B B. 45 These legs are connected together at their upper ends by a cross-piece B². Near their lower ends they are connected by cross-round B³. The cross-bar B² is hinged by means of 50 hinges *b b* to the transverse cleat or bar B', secured to the under side of the incline A, near the end thereof. One of the faces of the

cross-bar B² is made beveling or inclined, as shown in Fig. 1, so that when the legs have been extended into a vertical position said beveled edge may be in close contact with 55 the inclined under surface of the board A. As the frame for these legs is hinged in the manner stated it will be obvious that the legs may be conveniently folded. They may be removed from the vertical position which they 60 are seen occupying in Fig. 1, following the dotted lines, until they come in contact with the under side of the incline, as shown in Fig. 3.

Midway of the length of the incline A, I 65 provide another pair of supporting-legs C C. These legs are connected at their upper ends by the cross-bar C², and near their lower ends they are connected by the cross-round C³. The cross-bar C² is hinged by means of hinges 70 *c c* to the transverse cleat or strip C', secured to the under side of the incline; also, one edge of the bar C² is beveled, so that when the legs C C are in their upright or vertical position the beveled edge may be in close 75 contact with the under face of the incline. It will thus be seen that the construction and arrangement of the legs C C are similar in all respects to the construction and arrangement of the legs B B. The legs C C, since their 80 frame is hinged, are adapted to be folded. They may be moved out of the position shown in Fig. 1, following the dotted lines until they assume the folded position indicated in Fig. 3.

D designates a flat longitudinal spring secured by means of screws, which pass through the middle portion thereof, to the under side of the incline A. This longitudinal spring may extend from the lower pair of legs C C to the upper pair of legs B B, or it may 85 be of any length sufficient to constitute a good strong durable spring; but whatever its length may be its upper end must reach the cross-piece B². The upper end of the longitudinal spring D is provided with a slot 90 or groove in such a manner as closely to receive the lower edge of the cross-piece B², and is designed by the use of said groove to hold the pair of legs B B securely in position when extended, and when closed to hold the 95 legs B B securely back against the under side 100 of the inclined surface A.

D' designates another flat longitudinal spring constructed in all respects like the longitudinal spring D, and designed to operate upon the pair of legs C C precisely as the 5 longitudinal spring D operates upon the pair of legs B B.

In order to provide means for easily ascending to the highest end of the toboggan-slide, I make use of a series of steps, which are 10 hinged to the legs B B, so that they may be likewise folded when the legs are folded. E E denote the side pieces for these steps, F F being the horizontal steps, of which there may be any number, said steps F F being secured 15 firmly to the sides E E. These sides are preferably made of curved pieces of wood, and they are properly formed near the upper end thereof to permit of their being pivoted or otherwise movably connected to the legs B B, 20 as shown in Fig. 1. It will thus be manifest that when the legs are folded the steps will be folded between them. (See Fig. 3.) Thus the whole device may be neatly and compactly folded together, and when it is desired 25 to place it in position for use the legs and steps can be easily unfolded and caused to assume the positions delineated in Fig. 1.

Having thus described my invention, what I 30 claim as new, and desire to secure by Letters Patent, is—

1. A toy toboggan-slide consisting of an incline having its lower end resting upon the ground or floor and its upper end elevated at a proper distance from the floor, the pair of

legs connected to the upper end of the incline, 35 and the folding steps for mounting upon the incline, said steps being hinged to the said pair of legs, substantially as described.

2. The combination of the inclined surface, the end pair of folding legs hinged thereto, 40 the middle pair of folding legs hinged thereto, the longitudinal flat springs, having their opposite ends acting to hold the legs, and the folding step hinged to the end legs, substantially as described. 45

3. The combination, with the inclined part having its lower end resting upon the ground or floor, of the legs connected to the under side of the incline at the upper end thereof, the pair of shorter legs connected to the under 50 side of the incline, and the folding steps for mounting the incline hinged to the said pair of end legs, substantially as described.

4. The combination of the incline A, legs B B, suitably connected and hinged to the 55 bar B' on the incline, the legs C C, suitably connected and hinged to the bar C' on the incline, the flat springs D and D', having their opposite ends acting on the leg-frames, and the steps, consisting of steps F F and sides 60 E E, hinged to the legs B B, substantially as described.

In testimony whereof I affix my signature in presence of two witnesses.

Alice Miriam Wood.
